Des. 235,225
Patented May 27, 1975

235,225

CHANGEABLE SIGN

Steven Kramar, 4052 W. 26th St.,
Chicago, Ill. 60623

Filed Nov. 20, 1970, Ser. No. 26,092

Term of patent 14 years

Int. Cl. D20—03

U.S. Cl. D96—12

FIG. 1.

FIG. 5.

FIG. 2.

FIG. 3.

FIG. 4.

FIG. 1 is a front elevational view of a changeable sign showing my new design, with the rear being the same as the front shown;

FIG. 2 is another front elevational view thereof, with different indicia illustrated;

FIG. 3 is a rear elevational view of the movable indicia panel;

FIG. 4 is a front elevational view of the movable indicia panel; and

FIG. 5 is a cross sectional view taken on line 5—5 of FIG. 1.

I claim:

The ornamental design for a changeable sign, as shown and described.
